(74) Attorney, Agent, or Firm—William E. Pelton, Esq.

(57) **CLAIM**

The ornamental design for a tool case, as shown.

DESCRIPTION

FIG. 1 is a perspective view of the tool case showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plain view thereof;

FIG. 7 is a bottom plain view thereof;

FIG. 8 is a perspective view showing an inner dividing plate attached inside the tool case;

FIG. 9 is an another perspective view showing the inner dividing plate at different inclined angle; and,

FIG. 10 is a partially enlarged cross-sectional side plan view of the tool case along line 10—10 in FIG. 9 showing an engraved cutout formed on the inner plate.

The broken line portions of the disclosure are for illustrative purposes only and form no part of the claimed design.
